UNITED STATES PATENT OFFICE.

HENRY E. FRANKS AND ALBERT GEERDTS, OF BERKELEY, CALIFORNIA; SAID GEERDTS ASSIGNOR TO SAID FRANKS.

WINDOW-SASH BALANCE.

1,006,643.

Specification of Letters Patent. Patented Oct. 24, 1911.

Application filed February 2, 1911. Serial No. 606,223.

To all whom it may concern:

Be it known that we, HENRY E. FRANKS and ALBERT GEERDTS, citizens of the United States, residing at Berkeley, in the county 5 of Alameda and State of California, have invented new and useful Improvements in Window-Sash Balances, of which the following is a specification.

This invention relates to a window-sash balance, and particularly pertains to a means 10 for balancing slideable vertically hung windows.

It is the object of this invention to provide a device for balancing a window-sash 15 which is simple in construction and economical in manufacture, which can be quickly and easily installed and which occupies but small space.

A further object is to provide a substitute 20 for the balance weights now commonly employed in window construction, which, by reason of the space required for their operation, are in many cases objectionable.

The invention consists of the parts and 25 the construction and combination of parts, as hereinafter more fully described and claimed, having reference to the accompanying drawings, in which—

Figure 1 is a front elevation of a window 30 with parts broken away showing the invention as applied. Fig. 2 is a vertical section of the invention. Fig. 3 is an end elevation of same. Fig. 4 is a side elevation of a modified form of the invention partly in 35 section.

In the drawings A and B represent the upper and lower sashes respectively of the ordinary double hung window, these sashes sliding in the usual frame C and separated 40 from each other by a parting bead as is common in this type of window construction. Sash cords 2—2' are attached to the upper ends of the side portions of each sash A—B in any suitable manner, which cords 45 extend upward through perforations in the head of the frame C into a space 3 thereabove, and pass over direction pulleys 4—4'. The ends of the cords 2—2' are attached to the periphery of a drum or reel at diamet- 50 rically opposite points, as shown in Fig. 2, in such manner that when the drum is revolved both cords 2—2' will wind thereon or unwind therefrom simultaneously when the sash is raised or lowered. This reel or 55 drum is constructed as shown in section in

Figs. 2 and 4, the drum proper consisting of a hollow cylindrical member 5 rigidly mounted on an end plate 6, on which a hub is centrally formed.

A loose end plate 6', corresponding to the 60 plate 6, is placed against the other end of the cylinder 5 and has lugs 7 on its inner face which project into notches on the edge of the cylinder 5. The end plates 6—6' extend beyond the outer face of the cylinder 5 65 and form the side flanges of the reel, and are adapted to be revolvably mounted on a shaft 8 which extends through the hubs formed on the plates 6—6' and is supported at its outer ends on stirrups 9 pivoted on 70 standards 9'; these standards rising from a base plate 10 and disposed in contact with the plates 6—6'. The shaft 8 is in the form of a cotter-pin, that is, split a portion of its length and provided with an eye at its outer 75 end.

Wound on the interior of the drum 5 is a coil spring 11, the outer end of which is secured to the drum in any suitable manner, the inner end of the spring 11 being bent so 80 as to pass through the slot in the shaft 8. From this it will be seen that the spring 11 may be wound on the shaft 8 by revolving the latter and holding the drum against rotation.

Means are provided for facilitating the rotation of the shaft 8 to wind the spring 11 and for preventing its being rotated by the spring 11 when the latter is wound thereon under tension. This means consists of a 90 pin 12, which is inserted through the eye in the end of the shaft 8. This pin affords a handhold by which the shaft 8 may be rotated, and, when the spring 11 is sufficiently wound, provides means for preventing the 95 shaft 8 from being rotated, the pin 12 then being engaged by a link 13 attached to the plate 10, as shown in Fig. 3, or a pin 12' may be inserted in a pocket 14 formed on the standard 9', as shown in Fig. 4. 100

The spring 11 being wound on the shaft 8 under tension, and the latter being in a fixed position, the drum 5 will tend to rotate by reason of the circumferential pull of the spring 11. This pull of the spring 11 is 105 transmitted through the drum 5 to the cords 2—2' and tends to wind the latter on the drum. By adjusting the tension of the spring 11, through the shaft 8, so that the upward pull on the cords 2—2' will balance 110

the downward pull of the weight of the window sash A—B, the sash will be sustained in any position it is placed in the frame C, the spring 11 thus counterbalancing the sash.

The suspended mounting of the drum or reel from the pivoted stirrups 9 is for the purpose of equalizing the pull on the cords 2—2'. These cords 2—2', winding as they do in a number of coils on the reel, sometimes wind unevenly so that one cord would be apt to slack while the weight of the sash would be thrown on the other, but by suspending the drum it is free to swing so that the cords will be constantly kept taut. The standards 9' are slotted at 15, through which slots the shaft 8 extends, the slots being curved on a radius from the center of the pivotal point of the stirrups 9 to admit of the oscillating movement of the latter. In some instances the stirrups 9 may be dispensed with, in which event the shaft 8 will be mounted on the standards 9', as shown in Fig. 4.

From the foregoing it is apparent that when the sash A—B is raised, the spring 11 in recoiling will cause the cords to wind on the drum 5 and that when the sash is pulled downward, the cords 2—2' will cause the drum 5 to rotate to rewind the spring on the shaft 8.

Having thus described our invention, what we claim and desire to secure by Letters Patent is—

1. A window-sash balance, comprising a reel, a shaft on which the reel is revolvably mounted, a swinging support for the shaft, a coil spring disposed between the reel and the shaft and windable on the latter, said spring being adapted to rotate the reel by unwinding from the shaft, means for rotating said shaft to adjust the tension of the spring, and means for locking the shaft against rotation.

2. The combination with a window-sash and frame, of cords attached to each vertical edge of the sash, a reel on which said cords are wound in the same direction, a shaft on which said reel is revolvably mounted, a swinging support for the shaft, and a coil spring wound on the shaft and attached to the reel, said spring adapted to rotate the reel to wind the cords thereon when the weight of the sash is removed therefrom.

3. The combination with a window-sash and frame, of cords attached to each vertical edge of the sash, a reel on which said cords are wound in the same direction, a shaft on which said reel is revolvably mounted, a swinging support for the shaft, a coil spring wound on the shaft and attached to the reel, said spring adapted to rotate the reel to

wind the cords thereon when the weight of the sash is removed therefrom, means for rotating said shaft to adjust the tension of the spring, and means for locking the shaft against rotation.

4. A window-sash balance embodying a hollow cylindrical member, an end plate integral with one end of the cylinder, a loose end plate interlocked with the other end of the cylinder, a shaft upon which said end plates are revolvably mounted, said plates extending beyond the periphery of the cylinder to form side flanges, a swinging hanger for the shaft, and a coil spring wound on and connected to said shaft inside of said cylinder, one end of said spring attached to said cylinder.

5. A window-sash balance embodying a hollow cylindrical member, an end plate integral with one end of the cylinder, a loose end plate interlocked with the other end of the cylinder, a shaft upon which said end plates are revolvably mounted, said plates extending beyond the periphery of the cylinder to form side flanges, a swinging hanger for the shaft, a coil spring wound on and connected to said shaft inside of said cylinder, one end of said spring attached to said cylinder, said spring adapted to unwind from the shaft to rotate said cylinder, means for rotating said shaft to adjust the tension of the spring, and means for locking the shaft against rotation.

6. A window-sash balance, comprising a reel, a shaft on which the reel is revolvably mounted, and a coil spring disposed between the reel and the shaft and windable on the latter, said shaft mounted on swinging stirrups.

7. The combination with a window sash and frame, of cords attached to each vertical edge of the sash, a reel on which said cords are wound in the same direction, a shaft on which said reel is revolvably mounted, a coil spring wound on the shaft and attached to the reel, said spring adapted to rotate the reel to wind the cords thereon when the weight of the sash is removed therefrom, means for rotating said shaft to adjust the tension of the spring, said means including a cross pin in the shaft, means engaging the cross pin for locking the shaft against rotation, and means by which the shaft is allowed a lateral swinging movement.

In testimony whereof we have hereunto set our hands in the presence of two subscribing witnesses.
